LAST STAND

Victor J. Levaggi, Jr., Beverly, Mass., assignor to
 United Last Company, Portland, Maine, a corporation of Maine

Application February 17, 1945, Serial No. 578,397

3 Claims. (Cl. 12—15.1)

The purpose of this invention is to provide improvements in stands for supporting lasts while shoes are being placed on and removed from the lasts. The invention is herein illustrated in a form that was designed for two-part lasts of the type set forth in my application for United States Letters Patent Serial No. 555,434, filed September 23, 1944.

A last of the type above identified comprises a heel part and a forepart connected by a link and pivot pins. A latching shoulder formed on the link is arranged to cooperate with a pin carried by the heel part, but it may be unlatched from that pin to permit collapsing movement of the parts connected by the link.

The present invention is embodied in an improved combination comprising a last-supporting post or spindle and a lever partially nested therein, the spindle having a mortise partly in, and partly below, the portion intended to extend into the socket in the heel part of a last. One arm of the lever is nested in this mortise and is arranged to extend into the socket to a point above a retaining shoulder formed by a slot in the longitudinal wall of the socket. The nested arm of the lever is provided with a latching shoulder arranged to catch the retaining shoulder of the socket.

The portion of the latching arm that extends above the latching shoulder is provided with a camming surface by which it will be forced into the mortise in the spindle by the lower end of the socket as the last is pressed down to its seat on the spindle. If the last is of the type above specified, the camming surface of the latching arm will engage the link of the last when the latching arm is rocked to its last-retaining position, and such rocking will disengage the link from its latching pin to permit collapsing movement of the forepart.

The lever above mentioned is preferably in the form of a bell-crank, one arm thereof being arranged below the latching arm to serve as an operating handle and being so related to its fulcrum that the force of gravity will normally maintain the lever in its latching position. Moreover, if the post or spindle is rotatably arranged in a step bearing, the operating arm of the lever will serve to turn it about its axis to place the lever and the last in their cooperative relation.

Referring to the drawing,

Fig. 1 is a vertical section of a last and a last-stand in assembled relation but not interlocked;

Fig. 2 is a similar section of the interlocking

parts of the last and the stand in their interlocked relation;

Fig. 3 is a horizontal section through the parts intersected by line III—III in Fig. 2; and

Fig. 4 is a perspective view of the last-engaging elements of the stand.

To facilitate comparison of the present description with that in the related application Serial No. 555,434, the elements are identified by the same reference numerals in both cases, although the utility of the stand is not limited to lasts embodying all the features herein illustrated.

The last comprises a forepart 10, a heel part 11 and a link 27 connecting them. The parts 10 and 11 are divided, one from the other, to provide oblique joint surfaces and stop shoulders. A heightwise kerf 23 in the forepart, and a heightwise kerf 24 in the heel part are provided to receive the link 27 and a leaf-spring comprising arms 31 and 32 and a connecting portion 30. The link and the forepart are connected by a pivot pin 25, while the link and the heel part are connected by a latching pin 26. When the parts 10 and 11 are in last-forming relation the pin 26 cooperates with a latching shoulder 29 formed on the link and defining a portion of a slot 28.

The spring arm 31 is connected to the heel part by a pin 34 and thereby sprung away from the arm 32 which is thereby stressed to maintain the link 27 in its latching position (Fig. 1). The rear end of the link is thereby held in an opening 35 in the front wall of a cylindrical socket member 22 in the heel part.

The stand comprises a base 36 adapted to be fastened to a bench, and bored to provide a step bearing for a rotatable post or spindle 37 journaled therein. The last-engaging portion 41 of the spindle is cylindrical and of a size to enter the socket member 22. A collar 42 affixed to the spindle by a setscrew 43 is arranged to be seated on the upper end of the step bearing to support the spindle and to maintain an annular groove 44 therein at the level of a retaining key 45 screwed into the base. The key, when correctly adjusted, provides a swivel connection that merely prevents withdrawing the spindle from its bearing.

A mortise 46 is formed in the spindle, partly in the last-engaging portion 41 thereof and partly below the latter to receive a latching arm 40 of a bell-crank lever. A lower arm 38 of this lever projects from the mortise to be grasped and operated manually. The handle portion thereof is partly broken away in Fig. 1. The lever and the spindle are connected by a fulcrum pin 39.

The latching arm 40 has a latching shoulder 47 arranged to be projected from the mortise into the opening 35 in the socket member (Fig. 2) and thereby lock the heel part 11 on the spindle by engagement with the retaining shoulder 48 defining the lower end of the opening. If a last of the type shown is mounted on the spindle, the link 27 will be deflected by the latching arm 40 when the latter is rocked to its latching position, and the link will be thereby released from the latching pin 26. The forepart 10 may then be lifted and rocked over the heel part while the latter remains locked to the stand.

The weight of the operating arm 38 normally projects the latching arm from the peripheral surface of the portion 41 (Fig. 3), thus exposing a camming surface 49 above the latching shoulder 47. When a heel part is pressed down on the portion 41 the lower end of the socket member 22 may engage the camming surface 49 and thereby rock the latching arm into fully nested relation with the spindle, or, in some cases, the latching arm may be rocked by lifting the operating arm. In any event, the operating arm may also be used to turn the spindle about its axis to bring the latching shoulder 47 into register with the opening 35 in the socket member.

The bell-crank lever is provided with a finger 50 for limiting its range of rocking movement when no last is mounted on the stand. The finger is arranged to engage either of two adjustable stops 51 and 52 screwed into the collar 42.

When using the described stand to hold a last while a shoe is being placed on the last, an operator will first lock the heel part to the stand as hereinbefore explained and rock the forepart to shorten the last. After placing the forepart of the shoe on the forepart of the last, he will press it down to restore the true form of the last, and if the parts 10 and 11 are connected by a link of the type herein shown, the spring arms 31, 32 will return the link to its latching position (Fig. 1) and thereby force the latching arm 40 and the shoulder 47 thereof into the mortise 46 in the spindle. The heel part of the last may then be stripped from the spindle. On the other hand, if a last has some other type of means connecting the forepart and the heel part, but a socket provided with an opening 35 and a retaining shoulder 48, the operator will raise the arm 38

manually to retract the latching shoulder 47 into the mortise when he is about to strip the last from the spindle.

Having described my invention, what I claim as new and desire to secure by Letters Patent of the United States is:

1. A last stand comprising a base, an upstanding last-engaging spindle having a mortise partly in and partly below its last-engaging portion, and a lever having a latching arm arranged in the mortise and an operating arm projecting from the mortise below the last-engaging portion of the spindle, said latching arm having a latching shoulder arranged to be nested in the last-engaging portion of the spindle and to be projected laterally therefrom into an opening in the longitudinal wall of a last socket.

2. A last stand comprising a base, an upstanding last-engaging spindle having a mortise partly in and partly below its last-engaging portion, and a lever having a latching arm arranged in the mortise and an operating arm projecting from the mortise below the last-engaging portion of the spindle, said latching arm having a latching shoulder and a camming surface above it both arranged to be nested in the last-engaging portion of the spindle and to be projected from the peripheral surface thereof, said camming surface being arranged to be deflected into the mortise by the lower end of a last socket as the last is pressed down thereon, and said shoulder being arranged to cooperate with a corresponding shoulder in the longitudinal wall of the socket.

3. A last stand comprising a step bearing, a spindle journaled therein, means providing a swivel connection of said bearing and the spindle, the spindle having a cylindrical last-engaging portion above said bearing and a mortise in said portion, and a bell-crank lever having an upper arm nested in said mortise and a lower arm projecting laterally therefrom, said upper arm having a latching shoulder arranged to cooperate with a corresponding shoulder in the longitudinal wall of a last socket, and said lower arm being arranged to be grasped and operated manually to turn the spindle about its axis and to rock said upper arm into and out of said mortise.

VICTOR J. LEVAGGI, JR.
